AUTOMOBILE WINDOW SLIDING LOCK

Daniel L. Chandler, Somerville, Mass., assignor, by direct and mesne assignments, of thirteen per cent to Edwin M. Bailey, Swampscott, Mass., twenty-two per cent to George W. Ewing, Peabody, Mass., twenty-two per cent to Eugene B. Fraser, Lynn, Mass., ten per cent to Eugene B. Fraser, Lynn, Mass., as trustee, twenty-five per cent to Fred H. Rowe, Gloucester, Mass., and eight per cent to William H. Davis, Lynn, Mass.

Application January 16, 1936, Serial No. 59,376

6 Claims. (Cl. 292—275)

My present invention relates to locks and more particularly to an automatic friction lock which is mounted upon a rack and which may be slid along said rack and locked at any desired position on the rack by one operation of the operator.

My sliding lock is particularly adapted for use with automobile doors for raising and lowering and locking the sliding sash in such doors it being apparent, of course, that such a sash lock 10 may be used in other sashes exclusive of automobile doors. With such a sash lock as above referred to it is necessary that there be a lever or other equivalent actuating element associated with the raising and lowering sash mechanism, 15 as in my copending application entitled "Window elevating mechanism", Ser. No. 59,375 filed January 16, 1936, in which my present sash lock has been briefly indicated.

The principal object therefore, is an improved 20 sliding sash lock for automobile doors and the like.

Another object is a sliding sash lock which may be slid in a horizontal direction along a window sill, for instance, for the purpose of raising 25 and lowering the sash and at the same time automatically locking such sash when the handle of said lock is released.

Other objects and novel features comprising the construction and operation of the device 30 will be apparent as the description of the same progresses.

Referring to the drawing illustrating the preferred embodiment of my invention,

Fig. 1 is a side elevation showing the side of 35 the lock facing toward the outside of the door;

Fig. 2 is another side elevation similar to Fig. 1 but showing the lock in a released position, the dot and dash lines showing the same lock released when the handle is thrown in a reversed 40 direction, and

Fig. 3 is a vertical cross-section taken on the line 3—3 of Fig. 2.

Referring more in detail to the drawing, 45 indicates the outside panel of an automobile door. 11 indicates an inside panel of the door to which is usually attached the upholstery. On the inside face of the panel 11 at a point below the window sill I have attached a horizontal rack 12 by means of screws 13 and spacing collars 14.

The lock mechanism proper is mounted upon a plate 15. Back plates 16 and 17 are secured to the front plate 15 by means of screws 18, the plates being separated at the top by a gib 19 55 upon which the top of the rack 12 rides and

lower gib 20 and 21 against which the rack teeth are guided. A pinion 22 engaging the rack teeth is secured between the plates 15 and 17 being solidly fixed to a sleeve 23 which is journaled in the plates 15 and 17. Pressed on the sleeve 23 on the front of the plate 15 is a brake drum 24. Surrounding the drum 24 is a coil spring 25 the inside diameter of which in its normal position is slightly smaller than the outside diameter of the drum 24. The two ends of the spring 25 are hooked as shown at 26 above studs 27. Below the drum 24 and engaging the outer diameter of the spring coils is an angle member 28 which is secured by means of the screw 29 and dowels 30 to the plate 15.

When the sash lock is in the position indicated in Fig. 1 the spring 25 grips the drum 24 tightly and if the lock is pushed to the right or left through a force applied to the bottom of the lock through the lever 31 which is pivoted to the 20 plates 15 and 17 at 31^a, the pinion which engages the rack teeth cannot turn because the hooked ends 26 of the spring engage on one or the other of the studs 27, depending on the direction of the outside force applied, and the turning of the drum 24 tends to tighten up the coils of the spring 25 making it impossible for the lock to travel on the rack 12. Because of this locking feature it is impossible for the locking mechanism connected to the door and sash 32 30 to be acted upon by any force applied to the sash itself. The only way that the sash 32 can be moved is by an application of force applied to the lever 33 which is pivoted to the plate 15 at 34.

When a force (F) is applied in either direction, as indicated by the arrows in Fig. 2, the lever 33 operates like a cam on the top of the pivoted lever 35. The lever 35 pivots down on the pivot 36, the cam surface 37 and the extension dog 38 bear against the hooked ends 26 of the spring 25 pushing them against the studs 27. The pressure of the lever 35 on the spring 25 tends to uncoil the spring increasing its internal diameter such that the drum 24 is released. As the pressure at (F) is continued the entire lock 45 moves to the right or left, as the case may be, and any sash elevating mechanism which may be attached to the lever 31 is operated to open or close the sash. When the pressure at (F) is discontinued and the lever 33 released, the spring 50 which bears against the under side of the lever 35, returns the lever 35 to its normal position as shown in Fig. 1, the spring 25 automatically seizing the drum 24 and preventing it from turning 55

ing further thereby locking the pinion 22 in the rack teeth.

Having thus described my invention what I claim as new is:

- 5 1. An automobile window lock comprising a rack, a lock casing slidably mounted upon said rack, a pinion journaled in said casing and engaged with the under side of said rack, a friction drum solidly fixed to said pinion, a coil 10 spring tightly engaged around said drum, hooked ends formed on said spring, studs located adjacent said hooked ends on said spring being normally out of engagement with said hooked ends, a pivoted lever located above the said hooked ends and 15 normally held out of engagement with said hooked ends, a pivoted lever located above the said first pivoted lever and adapted to depress said first lever against said hooked ends when said second lever is swung to one side or the other of said casing, a pivoted lever attached to the bottom of said casing and adapted to be connected with a window sash operating mechanism.
- 20 2. An automobile window lock comprising a rack, a lock casing mounted on said rack, a friction drum and pinion mounted on said casing, the said pinion engaging with said rack, a coil spring normally smaller on its internal diameter than said drum and adapted to be engaged over said drum, studs located in the side of said casing adjacent said spring, anchor ends located on said spring, pivoted cam levers attached to said casing normally out of engagement with said anchor ends and adapted to engage said anchor 25 ends with said studs for the purpose of disengaging said spring around said drum, a lever pivoted to said casing and adapted to be connected to a window sash elevating mechanism.
- 30 3. In a locking device for a sash elevating mechanism, the combination of a stationary rack, a 35 sliding casing mounted upon said rack, a fric-

tion drum and pinion mounted on said casing, the said pinion engaging with said rack, a coiled spring friction brake tightly engaged around said drum, cams adapted to spread said spring, a pivoted lever attached to said lock and adapted to connect with said sash elevating mechanism. 5

4. In a locking device for a sash elevating mechanism, the combination of a stationary rack, a friction drum attached to said pinion on the outside of said casing, a coil spring with anchor 10 ends tightly engaged around said drum in its normal position, pivoted cams adapted to expand said coil spring around said drum, a lever attached to said casing adapted to form a link between said lock and said sash elevating mechanism. 15

5. A lock for automobile sashes comprising a fixed rack, a lock casing mounted upon said rack, a pinion continuously engaged with said rack, a friction drum attached to said pinion, a friction coil spring normally contracted and mounted around said drum, cams located adjacent said spring adapted to expand said spring for the purpose of releasing said spring from around said 20 drum, and a sash operating link attached to said 25 lock.

6. A lock for locking and operating a window sash and maintaining said sash in a locked position comprising in combination, a rack, a lock casing slidably mounted on said rack, a lock 30 pinion engaging in said rack, a friction drum connected with said pinion, a coil spring normally engaging around said drum in a tight manner and having hooked ends, cam levers attached to said casing and adapted to engage with 35 the hooked ends of the said spring, a pivoted link attached to said casing and adapted to be connected with the operating mechanism connected with the elevating mechanism of said sash. 40
